FILING CABINET GUIDE-SEPARATOR

Irving R. Cornish, Elmhurst, Ill., assignor of one-third to George Noble Paxton and one-third to John Warren Paxton, both of Bloomington, Ill.

Application December 18, 1943, Serial No. 514,789

1 Claim. (Cl. 129—16)

This invention relates to guide-separators for containers of vertical filing cabinets and has for its main objects the provision of an improved container and guide-separator construction whereby a plurality of guide-followers are held in easily-shiftable but irremovable vertical positions; to provide an improved construction of container and guide-separator particularly suitable for the type of filing cabinet known as "side filing;" to provide an improved arrangement of this kind particularly adapted for "side filing" cabinets wherein the container comprises a pair of right angle side members and ends and is mounted to revolve on a horizontal axis between its open and closed positions, whereby in its closed position one side becomes the supporting bottom, and in its open position the other side becomes the supporting bottom; and to provide an improved construction of this kind which is exceedingly simple and inexpensive to manufacture and highly effective in use.

Fig. 1 is a perspective view of such a two-container cabinet, one of the containers being shown in its open position empty so as to more clearly illustrate the mounting of the guide-separator of the preferred type.

Fig. 2 is an enlarged side elevation of the guide-separator and a fragmentary corner portion of the container showing the mounting of the preferred form of guide-separator.

Figs. 3 and 4 are enlarged fragmentary opposite views of the upper outer corner of the guide-separator showing the arrangement of the indexes.

Fig. 5 is an enlarged cross sectional view taken on the line 5—5 of Fig. 3 showing the arrangement whereby the index is held in place.

Fig. 6 illustrates the arrangement of the index tabs.

Fig. 7 is a view similar to Fig. 2 showing a modified arrangement for mounting the guide-separator in the container.

The "side filing" cabinet, for which this improved guide-separator is particularly designed for use, comprises a container 7 mounted in a casing 8 on horizontal pivots (not shown) so that the container is swingable between a closed position, as shown in the upper part of Fig. 1, and an open position, as shown in the lower part of said figure. The container 7 comprises a pair of members 9 and 10 arranged at right angles and a pair of end members 11. The pivots are so formed and positioned that when a container is swung into its closed position, as shown in the upper portion of Fig. 1, the contents are com-

pletely enclosed within the casing 8, but when swung into its open position, as shown in the lower portion of Fig. 1, are exposed for examination and removal and replacement horizontally sidewise rather than vertically. In the closed position of the container, the member 9 serves as a bottom for supporting the contents of the container, whereas, in its open position, the member 10 becomes a bottom upon which the 10 contents of the container rest.

This improved type of guide-separator 12, herein shown, comprises a piece of heavy fiber board or other suitable material and is formed with a shouldered tongue or extension 13 which has sliding, interlocking engagement with a groove 14 formed in the container 7. This tongue and groove arrangement retains the guide in a vertical, transversely held position but permits its ready shifting longitudinally of the container 7. The size and positioning of the guide-separator is such that the upper outer corner extends beyond the end of the contents, represented by the line 15 of Fig. 2, thus exposing to observation the usual indexes 16 required for filing cabinets. Moreover, the forward edge is cut away on a diagonal as shown. This avoids the possibility of the advancing corner of the guide, when the container is being swung open, from catching on the casing. Also, it allows the files 20 between the guide-separators to be grasped for removal without the danger of the separators being likewise grasped and accidentally withdrawn.

Two forms of the retaining tongue or extension 13 and groove 14 are shown. The preferred 35 form is that shown in Figs. 1 and 2. In that arrangement, the tongue is in the form of an integral extension on the lower inner corner of the guide-separator providing shoulders 17 and 18 rearwardly and below the edges of the guide-separator. The corresponding corner formed by the juncture of the members 9 and 10 of the container 7 is recessed, as shown in Figs. 1 and 2, so as to provide a shouldered channel or groove to receive the tongue or extension 13. The shoulders 17 and 18 interlock with the corresponding 40 shoulders of the groove 14 so as to secure the guide-separator in its vertical position against accidental removal transversely from the container 7 when any of the contents are being removed, while at the same time permitting it to be shifted longitudinally of the container to accommodate the addition or removal of contents.

In the modification shown in Fig. 7, the shouldered tongue or extension 13 is in the form of a 45 T integral with the rear edge of the guide-sep-

arator 12 intermediate its top and bottom edges. The member 9 of the container 7 is provided with a slot 14' which accommodates the neck part of the retaining tongue 13 and the edges of which provide shoulders 17' and 18' coacting with the transverse part of the T for retaining the guide-separator in position. This form possesses the same advantages as does the preferred form shown in Fig. 2.

With either form of the tongue or extension 13, the guide-separator 12 is placed in or removed from its operable position in the container 7 by turning the guide-separator to a slight angle from the horizontal sufficient to permit the tongue or extension to be set in or removed from the slot or groove 14 or 14'.

Indexes, of course, are required on the guide-separators. To that end, the corner of the guide-separator has attached a transparent tab holder 19 so as to provide pockets, between it and the guide-separator, into which may be slipped the doubled-over index tabs 16. With this arrangement it is possible to print two identical indexes on a single strip side by side in the same positions, as shown in Fig. 6, which may then be folded along a center line and inserted in the holders 19. The index is thus exposed to vision from either end of the container 7. This is a

convenience not possible in the "top filing" type of cabinet.

The operation of the guide-separator, it is believed, will be perfectly obvious from the foregoing description.

Other variations and modifications in the details of the structure and arrangement of the parts may be resorted to within the spirit and coverage of the appended claim.

I claim:

The combination of a vertical-file container and a guide-separator, said container having each of two right-angularly disposed walls thereof recessed along the faces adjacent the juncture of said walls so as to provide a corner channel with the recessed surfaces located inwardly of the respective right-angle faces of said walls and terminating at right-angle shoulders in the respective walls, said guide-separator having one corner formed with a right-angle extension conforming to the shape of and fitting in the corner channel of said container whereby said guide-separator is slidably supported in a vertical position in said container with said extension irremovable from said corner channel so long as said follower is retained approximately normal to both of said container walls.

IRVING R. CORNISH.
